UNITED STATES PATENT OFFICE.

CHARLES VICTOR ANDERSON, OF SALT LAKE CITY, UTAH.

CURTAIN-POLE-LIFTING DEVICE.

1,159,819.

Specification of Letters Patent.

Patented Nov. 9, 1915.

Application filed September 18, 1913. Serial No. 790,502.

To all whom it may concern:

Be it known that I, CHARLES V. ANDERSON, a citizen of the United States, residing at Salt Lake City, in the county of Salt Lake and State of Utah, have invented certain new and useful Improvements in Curtain-Pole-Lifting Devices, of which the following is a specification.

The present invention has for its object 10 to provide a simple and convenient device for removing suspended articles, such as curtain poles and the like, from their wall supports, whereby the operator, while standing in a position on the floor may readily dislodge and remove a curtain pole, for instance, from its support.

The use of the improved device obviates the necessity for employing step-ladders when hanging or removing curtain poles, 20 thus saving the housekeeper the time formerly employed in running up and down step ladders, as well as obviating the danger attendant their use.

A full understanding of the nature and 25 objects of the invention will be attained from the ensuing detailed description of a construction embodying the same in a preferred form, when taken in connection with the accompanying drawings, and the novel 30 features of the invention will be particularly pointed out and specified in the appended claim.

In the drawings: Figure 1 is a front elevation of a curtain pole lifting device embodying the present improvements. Fig. 2 is an end elevation thereof, with the lifting device shown disconnected from its handle. Fig. 3 is a front elevation of a modified 40 form of lifting device adapted for engagement with a picture wire, whereby a suspended picture may be removed from a wall. Fig. 4 is an end elevation of the device illustrated in Fig. 3 and also illustrating in end elevation a preferred construction for detachably mounting both forms of the lifting device on a handle.

Like characters of reference in the several figures indicate the same parts.

In the form of the invention illustrated in 50 Figs. 1 and 2, the lifting device or main supporting member 1 is conveniently embodied in an elongated bar 2 having curtain pole engaging and lifting clips 3 and 4' projecting upwardly from the respective ends 55 of the bar. Each lifting clip consists, preferably, of a plate having a flat base portion

secured to the bar 2, the plate being split longitudinally above the upper edge of the bar 2 to provide upreaching arms 4 and 5, bent outwardly in opposite directions from the plane of the bar and forming a seat with a free open end. As shown in Fig. 2, the free upper ends 6, 7, of the upreaching arms 4, 5 are bent slightly outwardly to prevent them from catching or marring the 65 pole while being slipped thereunder. The bar 2 is adapted to be attached to the upper end of a handle, a portion of which is illustrated at 14, and by manipulation of the handle, the clips at the ends of the bar 2 70 may be mutually slid freely into supporting engagement with a curtain pole. The handle 14 will be made long enough to permit the operator to reach the pole from a position on the floor and slip the clips under 75 the pole and lift it from its brackets or other wall supports, without having to mount a step ladder or stand on a chair.

In Figs. 3 and 4, the lifting device is slightly modified for use in removing pictures from the wall. Instead of the elongated bar 2, a bifurcated member 19 is employed, having its arms 17 and 18 split and bent apart to provide upreaching oppositely extending fingers 20 and 21. In operation, 80 the fingers 20 and 21 are slipped under a picture wire, by manipulation of the handle 14, and the picture removed by lifting the wire, supported by the arms 17 and 18, from its wall hook (not shown). Bifurcated 85 member 19 is provided with a circular extension 20' similar to extension 8, whereby it may be detachably mounted on the handle 14 in the manner hereinafter described.

Both forms of the lifting device are preferably so constructed that they may be detachably mounted on the end of handle 14 in different angular positions in the manner shown and described in my prior Patent No. 1,009,883, granted to me November 28, 1911. 100 For this purpose, the article support is provided with a depending substantially circular extension 8 having a central tubular bearing 9 projecting from one face thereof and extending clear through the extension to 105 the opposite face thereof. Arranged around the bearing 9 is a series of holes 10. Secured to the handle 14 is an upper extension 13, preferably circular and of the same diameter as the extension 8. Projecting from extension 13 is a central lug 11 and a series of lugs 12, each lug the same distance from the cen-

tral lug 11, as the holes 10 in extension 8 are from the tubular bearing member 9, whereby the lugs of extension 13 may be fitted into the holes of extension 8. A hook 15 is pivotally mounted at 16 on the handle 14 below the extension 13.

By an inspection of Fig. 4 it will be apparent that the central lug 11 of extension 13 may be inserted in tubular bearing member 9 of extension 8, and the lugs 12 in any of the holes 10, in accordance with the desired angular adjustment of the article support relatively to handle 14. By slipping hook 15 over bearing 9, the two extensions are rigidly secured together.

Having now described my invention that which I claim to be new and desire to procure by Letters Patent is:—

A device for lifting and removing curtain poles and the like from their wall supports,

Copies of this patent may be obtained for five cents each, by addressing the "Commissioner of Patents, Washington, D. C."

comprising, in combination, a handle, an elongated bar mounted on one end of the handle, a lifting clip projecting upwardly from said bar at each end thereof, each lifting clip consisting of a plate having a flat base portion secured to the bar, said plate being split longitudinally of the plate above the upper edge of the bar, to provide up-reaching arms bent outwardly in opposite directions from the plane of the bar to form a seat with a free open end, whereby the clips at the ends of the bar may be mutually slid into supporting engagement with a curtain pole by manipulation of the handle.

In testimony whereof I affix my signature in presence of two witnesses.

CHARLES VICTOR ANDERSON.
